ATTORNEY

UNITED STATES PATENT OFFICE.

ALETHA A. HOESE, OF WYNOT, NEBRASKA.

JAR PROTECTOR.

Application filed December 8, 1924. Serial No. 754,681.

To all whom it may concern:

Be it known that I, ALETHA A. HOESE, a citizen of the United States, residing at Wynot, in the county of Cedar and State of Nebraska, have invented new and useful Improvements in Jar Protectors, of which the following is a specification.

My present invention has reference to a glass or jar protector and may be considered in the nature of an improvement upon the construction disclosed in my Patent No. 1,238,669, granted August 28, 1917.

The primary object of my present invention is to simplify my patented construction by providing a hollow heat absorbing element designed to be arranged in a bottle or jar in which hot liquids are poured to partially absorb the heat therefrom and to prevent the sudden expansion of the jar and consequent breakage thereof, and wherein the heat absorbing element is removably and adjustably associated with a funnel that facilitates the pouring of the heated fluid into the jar or like container.

The drawings illustrate a satisfactory embodiment of the improvement as it now appears to me, and wherein:—

Figure 1 is a substantially central longitudinal sectional view through a jar with my improvement thereon, parts of the latter being in section.

Figure 2 is a fragmentary sectional plan view through the funnel to illustrate the manner in which the hollow stem of the heat absorbing member is associated therewith.

Figure 3 is a sectional view approximately on the line 3—3 of Figure 2.

The protector is substantially similar to the construction disclosed in my referred to Patent No. 1,238,669. The protector comprises a hollow stem 1 that has one of its ends formed with a hollow head 2. In the drawings, the head is substantially elliptical in plan and in side elevation, although the same may be otherwise shaped, and the hollow stem 1 is preferably slightly flattened throughout its length and also is preferably gradually widened from its connection with the hollow head 2 to its outer end.

The protector is preferably designed to be associated with a funnel 3 as disclosed by

the drawings. The funnel is preferably of metal as is the protector, although both of these elements may be constructed of any other desired material. The funnel has its mouth of a size to be snugly received in the mouth of a preserving jar 4, and the said funnel is provided with the usual handle 5. The funnel, on its inner face has secured thereon one end of spring clamps 6 and 7 respectively, the same being of different widths to snugly receive the tapered sides of the stem 1 therein. In this manner it will be noted that while the protector is removably associated with the funnel, the stem thereof may be readily slid through the spring clamps 6 and 7 in an outward direction through the funnel so that the head of the protector may be arranged on the bottom of varying sizes of preserving jars or the like.

While I have shown my improvement in connection with a preserving jar, it is to be understood that the same is not to be thus restricted in its useful capacity and that the improvement may be made of different sizes and lengths so that the same can be conveniently positioned in any class of breakage vessel in which heated liquids are to be poured. The theory regarding the operativeness of the improvement is well known. The device will absorb a part of the heat from the liquid delivered into the vessel in which the improvement is arranged. A portion of this heat will pass through the hollow stem but the outer end of the stem is retained in a practically cool condition. The absorption of the heat by the protector will prevent the sudden expansion of the glass jar or container and thereby avoid the liability of the breakage thereof.

As stated, the jar protector is substantially similar to the construction disclosed in my Patent No. 1,238,669. In my referred to patent I found it necessary to employ a slideable handle on the shank of the improvement in order that the same could be easily handled without injury to the user. With my present construction the means with which the protector is removably associated not only serves for holding the protector but also serves as a means for directing

heated fluid into a container, and when one container is filled the device as a whole may be lifted therefrom and arranged in a second container to be filled with heated water or other liquids. When the protector is removed the funnel may be employed in the usual manner.

Having described the invention I claim:—

A funnel designed as a holder for the stem of a glass protector, including a funnel member having spaced aligning spring clips on the inner face thereof.

In testimony whereof I affix my signature.

ALETHA A. HOESE.
